EDUCATIONAL ENTERTAINMENT DEVICE

Lee Burnett, Toledo, Ohio

Application April 22, 1946, Serial No. 664,088

4 Claims. (Cl. 46—131)

1

This invention relates to relatively movable elements adapted for range of set-up positions of rest.

This invention has utility when incorporated in special units for range of static positions of assembly, as an effigy or figure toy at balanced positions of stability upon a ladder upstanding at an angle of equilibrium for the effigy thereon.

Referring to the drawings:

Fig. 1 is a side elevation of an embodiment of the invention in a ladder, balanced into an upwardly inclined position by a jointed clown-like ness effigy, at a lower location for set-up or assembly as to the ladder, a portion of one of the rails of the ladder being broken away to show the foot of the effigy in its coaction with a ladder rung and.

Fig. 2 is a view similar to Fig. 1, but with the equilibrium established by the effigy at a higher ascent assembly with the ladder, a portion of a rail of the ladder being broken away.

Upon a firm horizontal flat base or support 1, may rest complementary flat face ends 2 of a pair of parallel side rails 3, 4, of a ladder type of miniature device having uniformly spaced therealong rungs 5. It is to be noted that the direction of the plane of the ladder end faces 2 is not at right angles to that of the ascent direction of the ladder side rails. Applicant has adopted an inclination of 15° as an inclination or forward pitch for the ladder rigid assembly element at which the extent of the face 2 from front to back establishes a region of stability, or a range in which it is desirable to develop a set-up for the toy in which the assembly center of gravity shall fall. When the assembly be so adjusted, it is static thruout, with no rocking or oscillation, even though there may be slight vibration of the support 1.

In the carrying forward of this achievement, a relatively shiftable element is provided. Furthermore, with joints, or relatively movable parts therefor, there is thereby multiplied the range of locations for stability, beyond the mere shifting to different assembly relations with the rungs of the ladder.

The additional device is of attractive form for entertaining children when incorporated as an effigy of clown-like contour and decoration, comprising a torso 6 with a pivot 7 for hinge mounting of a pair of lower limbs 8, 9.

In the ladder assembly, bottom of the foot arch 9' engages over a lower rung, as the top of toe portion 10 rides back of the next rung 5 upward. This establishes an outward location

2

for the pivot 7, herein slightly forward or away from the vertical or riser line 11, which means as against the normal weight or center of gravity for the ladder as to the right of this line 11 in Fig. 1, the pivot 7 is so located that the torso 6 may be at the opposite side of this line 11. The child, or one interested in this educational or amusement device has as the problem, so to shift the torso 6 on the pivot 7 that the center of gravity of the assembly with the ladder of this effigy shall be located within the extent of the ends 2 on the support 1.

A pivot 12 provides hinge mounting for arm-like elements 13, 14, which as swingable on the torso 6, may further disturb the center of gravity location. The pivots 7, 12, are sufficiently firm to hold frictionally, the limbs 8, 9, 13, 14, in a placed position therefor.

Ascent of the ladder, that is, a location for the effigy more remote from the support 1, requires for stability a rocking of the effigy or the limbs thereof further from the ladder. The attractiveness of the entertainment feature is that here is a ladder standing against nothing at its upper end, the ladder base being unattached, and the clown object being only foot-hooked therewith.

What is claimed and it is desired to secure by Letters Patent is:

30. 1. The combination with a first element having a planar face adapted to coact for support on a planar base with the element directed in an unstable riser direction therefrom, of a second element having selectable detachable support upon the first element by engagement spaced from the base directing the second element oppositely from the unstable direction of the first element to an extent to stabilize the first element.

2. An educational toy entertainment device 40 comprising a miniature ladder having a pair of side rails and connecting rungs, adjacent ends of the side rails forming a planar base to direct the ladder in a forward pitch unstable relation, and a jointed effigy including a torso and a hooking limb, said limb adapted to engage a ladder rung and the torso adjustable relatively thereto sufficient to neutralize the unstable pitch relation of the ladder.

3. A device for equilibrium set-up from a 50 planar base, said device comprising a riser member having a planar face to rest on the base for directing the member in unstable relation thereto, and an element adjustably connected to the member in extent oppositely from the direction 55 of the unstable relation to locate the vertical line

passing through the center of gravity of the assembled device within the bounds of the member planar face.

4. A first element ladder having a forward pitch direction from flat base portion at an obtuse angle to the ladder upward extent, and a second element of effigy type adapted for selective engagement with and to extend opposite from the ladder pitch, said effigy being adjustable relatively to the member in coacting to establish a balance for the assembly.
